UNITED STATES PATENT OFFICE.

FREDERICK E. PRETAT, OF WATERVILLE, CONNECTICUT.

TOILET BRUSH.

Application filed April 10, 1925. Serial No. 22,136.

This invention relates to brushes, and more particularly to a toilet brush adapted to be held in the hand and intended to be used without a handle.

5 One object of this invention is to provide a toilet brush of the above nature constructed from a closed loop of twisted wire having bristles projecting therefrom in all directions.

10 A further object is to provide a brush of the above nature in which the ends of the wire loop are bent inwardly so as to eliminate dangerous projecting parts.

15 A further object is to provide a brush of the above nature in which the ends of the wire loop are covered by a protective sheath.

20 A further object is to provide a toilet brush of the above nature which is adapted to be used in place of the common hand brushes, rubber sponges, and the like, usually employed.

25 A further object is to provide a device of the above nature which will be simple and practical in construction, inexpensive to manufacture, easy to manipulate, which may be readily cleaned, which will dry quickly, which will not be injured by hot or cold water, and which will be attractive in appearance, and very efficient and durable in use.

30 With these and other objects in view, there have been illustrated on the accompanying drawings, several forms in which the invention may be conveniently embodied in practice.

35 Fig. 1 represents a top plan view of a toilet brush made in the form of a circular wire loop, part of the bristles being removed for greater clearness.

40 Fig. 2 is a cross-sectional view of the same, taken along the line 2—2 of Fig. 1, looking in the direction of the arrows.

45 Fig. 3 is a top plan view of a third form of loop toilet brush, said brush being elliptical in shape and having an inwardly extending sheath for protecting the ends of the wire loop.

50 Fig. 4 is a perspective view of the sheath for covering the bent-in ends of the wire loop of the brush shown in Fig. 4, said sheath being shown in its original shape before it has been bent to fit around the ends of the loop.

55 Fig. 5 is a sectional view of the sheath shown in Figs. 4 and 5, the section being

taken along the line 6—6 of Fig. 4, looking in the direction of the arrows.

In previous forms of wire loop toilet brushes now commonly used, the handle of 60 the brush is often in the way and in some cases has been the cause of injury to the persons using them or to the materials being cleaned.

65 By means of the present invention the above and other disadvantages have been avoided. This has been accomplished by eliminating the handle from the brush and by covering the connected ends of the loop.

70 Referring now to the drawings in which like reference numerals denote corresponding parts throughout the several views, the numerals 10 and 11 indicate a pair of twisted wires bent in a circle to form a closed loop, 75 said wires holding tightly between them a multiplicity of bristles 12. In order to avoid projecting portions which might injure the hands or body of the user, the extremities 13 and 14 of the loop are arranged adjacent each other, being bent inwardly, 80 and then laterally in opposite directions about a ring 15 which serves to securely connect them.

85 In Figs. 4 to 6, a second modified form of toilet brush is disclosed, in which an elliptical twisted wire loop 19 is employed. The extremities 20 and 21 of said loop are bent inwardly in a radial direction, and are adapted to lie parallel to and in contact with one another. The extremities 20 and 21 are 90 connected by a protective sheath member 22 formed in the shape of a cup and having a pair of wire-receiving slots 23 and 24 in its open end, said slots being located between a pair of curved sections or flaps 25 and 26. 95

100 As will be understood, after the sheath member has been placed over the ends of the wire as shown in Fig. 4, the side flaps 25 and 26 may be bent inwardly by any suitable tool or tools until said flaps come into abutment, thereby rigidly connecting the extremities 20 and 21, and forming a smooth outer unobstructed surface. If desired, the interior of the sheath member 22 may be 105 filled with a suitable cement so as to form a stronger and more durable construction.

110 While the brushes herein disclosed are especially adapted for toilet use, it will be understood that they may also be employed, within the spirit of the invention, for dish washing, scrubbing pans, cleaning wood-work, cleaning fabrics, etc. It is also within

the spirit of the invention to employ wires instead of bristles, in which case the brush can be used for scratch-brushing or the like.

One advantage of this invention is that the ends of the closed wire loop are joined independently of any handle member, and the handleless brush comprises a complete toilet article in itself.

While there have been disclosed in this specification several forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a handleless toilet brush, a closed

loop of twisted bristle-holding wires, the ends of said loop being bent inwardly, means for locking said inwardly-bent ends together, the bristles of said brush projecting inwardly and outwardly, the outer portions of said bristles forming a continuous brushing surface extending around the periphery of said brush and completely covering the joint of the ends of said loop and said locking means, whereby all possibility of injury to the user will be avoided.

2. In a handleless toilet brush, a closed loop of a twisted bristle-holding core, the ends of said loop being bent inwardly and encased in a protecting sheath, said bristles forming an unbroken continuous brushing surface extending around the periphery of the brush and completely covering and concealing said sheath, so as to avoid injury to the hands or face of the user.

In testimony whereof, I have affixed my signature to this specification.

FREDERICK E. PRETAT
